PUNCHING MACHINE

William F. Gutgesell, Endicott, N. Y., assignor, by
mesne assignments, to International Business
Machines Corporation, New York, N. Y., a cor-
poration of New York

Application December 29, 1932, Serial No. 649,297

5 Claims. (Cl. 164—115)

This invention relates to punching or perforating machines and more particularly to machines of the type in which punching may be controlled either manually or by a previously punched card.

5 The principal object is to increase the general flexibility of a card reproducing or duplicating machine so that reproduction of certain data on a punched card may be effected in accordance with certain other data on the punched card. Where 10 it has heretofore been desired to reproduce data in particular fields of a punched card and to suppress data punched in other fields, so-called skip bars and column cut-out bars have been provided to effect a machine set-up whereby the same 15 fields of each punched card to be reproduced would be rendered active and the same fields in each suppressed.

In certain classes of work, this machine set-up is not sufficiently flexible where it is desired to 20 suppress or reproduce data in a particular field of the punched card accordingly as the card is punched in a specially designated field or not. Further mechanism is incorporated in the machine and may be operated in conjunction with 25 the regular column skipping and cut-out devices effective in certain fields of the punched card whereby upon the occurrence of a specially located perforation in such fields, the reading and reproduction of data in the field containing such 30 special perforation will be suppressed and the field automatically skipped. If the special hole is absent, all or part of the field may be effective to punch reproduction data in the new card.

35 Various other objects and advantages of the invention will be obvious from the following particular description of one form of mechanism embodying the invention or from an inspection of the accompanying drawings; and the invention also constitutes certain new and novel features 40 of construction and combination of parts herein-after set forth and claimed.

In the drawings:

Fig. 1 is a wiring diagram of the electric circuits 45 of the machine.

Fig. 2 is a detail in section of the punched card analyzing devices.

Fig. 3 is a detail of the column cut-out device.

Fig. 4 is a specimen of a card form.

50 Fig. 5 is a detail of the card carriage escapement mechanism.

Fig. 6 is a further detail of the card carriage escapement mechanism.

55 Fig. 7 is a detail of the essential operating elements of the punching section of the machine.

Fig. 8 is a detail of the punch controlling contact and the operating device therefor.

The punching machine is generally of the form shown in the Lee and Phillips Patent No. 1,772, 186, granted August 5, 1930 and the description 60 thereof will be limited to the features essential to an understanding of the present invention.

In Fig. 7, punch selecting magnets 10 are provided, there being one for each index point position of the record card. Energization of magnet 65 10 will attract its armature to rock an arm 11 in a counterclockwise direction about its pivot 12, thus moving key 13 downwardly to rock a bell crank 14 which has connection with an interposer 15 which is suitably mounted for horizontal reciprocation. The forward end of interposer 15 is 70 suitably guided between an operating bar 16 and the upper end of a punch 17.

Forward movement of the interposer will position its widest portion between bar 16 and punch 75 17 so that subsequent counterclockwise rocking of bar 16 about pivot 18 will move the interposer and punch downwardly to perforate the record card 19. A notch 20 in the interposer cooperates with a bail 21 to rock the same in a counterclockwise direction when the interposer is moved toward the left. Rocking of bail 21 in such manner will draw a hook-shaped member 22 (see Fig. 8) toward the left to close a pair of contacts 23.

As will be explained in connection with the 80 circuit diagram, contacts 23 complete a circuit through the punch magnet 24 causing it to attract its armature 25 and through linkage generally designated 26, draw downwardly on the bar 16 to cause depression of the selected punch. Depression of key 13 may, of course, be effected independently of the operation of the magnet 10 for the purpose of manually controlling punching operations.

Disposed beneath the interposers 20 is a bail 85 27 which is carried by rod 28 upon one end of which is secured an arm 29 (see Fig. 5) for operating the escapement mechanism. The escapement mechanism comprises a holding pawl 30 pivoted at 31 to the frame of the machine and a stepping pawl 32 loosely pivoted on rod 28 and normally urged by a spring 33 into engagement with the teeth 34 on the upper edge of the carriage rack 35. Rocking of rod 28 in a counterclockwise direction under action of an interposer 15 will lower pawl 30 into engagement 100 with a tooth 34 to hold the rack 35 in position while punching is being effected. This action at the same time raises pawl 32 out of engagement 105 with teeth 34 and by virtue of its loose connection 110

with rod 28 will move slightly toward the right in readiness to intercept the next tooth 34 when the rod 28 is returned to its original position.

Referring to Fig. 1, the rack 35 is suitably 5 mounted for horizontal movement in the frame of the machine and may be manually moved toward the right to the position shown wherein a record card 19 is placed in position with the first column thereof in line with the punches 17. 10 Gear teeth cut on the underside of the rack cooperate with suitable gearing 41 which is connected to the usual spring barrel 42 which tends to move the rack toward the left and which effects such movement under control of the escape- 15 ment mechanism just described.

Rack 35 is provided with extensions or arms 43 and 44 between which a pattern or master card 45 is positioned and which is adapted to be moved back and forth with the rack. An arm 46 carried by the rack 35 is provided for cooperation with the card 19 to move it column by column past the punches 17. Positioned above the pattern card 45 is a contact roller 47 (see also Fig. 2) which is insulated from the frame of the machine and supported by a door 36 pivoted at 20 37. A pair of contacts 38 is adapted to be closed when roller 47 is in its down position as in Fig. 2. Directly below the roller 47 is a row of brushes 48 carried by a bar 49 which is normally in the 25 position shown in Fig. 2 holding the brushes down out of engagement with the card 45. A magnet 50, upon energization, will attract its armature 51, actuating linkage 52 to cause upward movement of brushes 48 into engagement with the record card. This brush operating structure is fully shown and described in the copending application of Lee and Daly, Serial No. 391,874, filed September 11, 1929, to which reference may be had for further details of construction. A contact 53 is closed when armature 51 is attracted to elevate brushes 48 into contact with roller 47.

Referring now to Figs. 5 and 6, shaft 55 which carries the bail 21, is rocked from the position shown in Fig. 7 to that of Fig. 5 by the shifting 40 of an interposer 15 and a T-shaped element 56 secured to shaft 55 is rocked slightly counter-clockwise. A spring 57 is coiled about shaft 55 and has its ends abutting element 56 and an element 58 loose on shaft 55. Element 58 normally abuts a lug 59 of a member 60 loose on shaft 28, the result being that spring 57 is coiled about shaft 55 as the element 56 is rocked. When the stepping pawl 32 is subsequently rocked, the upper edge thereof, contacting with an arcuate 45 lug 61 of member 60, will elevate the latter, permitting the element 58 to follow element 56 under the influence of spring 57. Member 60 carries a pin 62 in its free end which, when member 60 is rocked, serves to open a pair of contacts 63 and close a pair 64. The function of these contacts will be explained in connection with the circuit diagram.

As bail 21 is returned to its normal position, member 56 will engage element 58 to rock the latter clockwise during the return movement of bail 21. By virtue of this construction contacts 63 and 64 remain in their shifted position until the advanced interposer is fully restored.

In Fig. 8 is shown an arm 55a secured to shaft 55 which is adapted to be engaged by an extension of link 26 to cause rocking of shaft 55 whenever the punch bail 16 is operated. This results in the actuation of contacts 63, 64 as though an interposer 15 had rocked the shaft.

Fig. 3 shows the mechanism for cutting out

reproduction punching in certain predetermined columns or fields to permit manual punching of the columns or fields cut out. This may comprise a bar 65 fixed to the base of the machine and which has cut-out portions 66 coextensive with the columns or field to be duplicated and cam portions 67 adapted to engage a lug 68 of lever 69 pivoted at 70 to carriage arm 43. Lug 68 presses against a bail 71 and rocks a rod 72 on which the bail is mounted. Projecting downwardly from the rod 72 is a finger 73 which upon turning of rod 72 as described opens a pair of contacts 74.

The mechanisms briefly described above are now well known in the art and further explanation thereof may be found in the patents referred to and in the application of Fred Lee and George F. Daly, Serial No. 391,874, filed September 11, 1929.

For the purposes of the present invention a brush carrier 75 is mounted upon arm 44 and provided with pairs of brushes 76 and 77. Brushes 76 are electrically connected and bridge a pair of contact segments 78 when the thirty-fourth column of the card 19 is under the line of punches 17 and bridge a second pair of contact segments 79 when the fifty-seventh column of the card is under the punches. Brushes 77 successively connect segments 80 and 81 with a common conducting segment 82. The several segments are imbedded in a support 83 of insulating material which is rigidly secured to the base of the machine.

The complete operation of the machine will now be traced with particular reference to Figs. 1 and 4. The latter figure shows a card of the "dual service" type used in connection with public utility statistics and accounting. The left hand portion of the card may contain data representative of the account number, meter reading dates, route location, date of payment, etc. The remainder of the card is divided into two similarly outlined fields labelled G and E, the former adapted to receive data concerning "gas" and the latter, similar data concerning "electricity". The card of a customer to whom both types of service are furnished will have data punched in both the G and E fields. The card of a customer to whom only one type of service is furnished will have only the field corresponding to that type of service perforated and a perforation 85 will be made in the first column of the unused field in the "11" index point position.

Assume that a punched card 45 has been placed in the appropriate card carriage and a blank card 19 in its carriage and that column cut-out bar 65 is cut so as to maintain contacts 74 open during the punching of certain of the first thirty-three columns of the card. In the columns to be key punched, contacts 74 will be open, and they will be closed in columns that are to be duplicated under control of the corresponding column of card 45. The punching in the first thirty-three columns is in accordance with the usual practice and a representative circuit will therefore be sufficient to explain the operation. Depression of any key 13 will close contacts 23 (Fig. 1) completing a circuit from source S, wire 94, contacts 23, punch magnet 24, wire 86, back to source S. This causes the perforation of the index point position corresponding to the key depressed and the automatic escapement of the cards to the next column.

In columns to be duplicated the following punch selecting circuit may be traced. From

- source S, wire 86, contacts 63, wire 87, roller 47, hole in card 45, brush 48, cable 88, corresponding magnet 10, wire 89, points 90a of relay 90, wire 91, relay 92, column cut-out contacts 74 (now closed), wire 93 to source S. Energization of magnet 10, causes selection of a punch and closure of contacts 23 which in turn complete the above traced circuit to the punch magnet 24 to effect punching and escaping.
- 10 When the thirty-fourth column of card 45 arrives at the brushes, contacts 74 are closed and brushes 76 bridge segments 78. If there is an "X" perforation in column 34 of card 45, the entire field G is to be skipped and this is effected
- 15 as follows: A circuit is completed from source S, wire 86, contacts 63, wire 87, roller 47, "X" perforation in column 34, brush 48, cable 88, wire 95, segments 78 (bridged by brushes 76), wire 96, relays 97, 90, wire 98, wire 93, to source S.
- 20 Energization of relay 90 which is of the quick acting type, opens its points 90a to prevent the perforating of the "X" position of column 34 of card 19. Relay 97 closes its points 97a to set up a holding circuit which extends from source S,
- 25 wire 99, common strip 82, brushes 77, strip 80, wire 100, points 97a, relays 97, 90, wire 98, wire 93 to source S. This circuit will hold throughout the analysis of the G field of card 45.

The G field is skipped by successive operations

30 of punch magnet 24 which is operated without accompanying punching. The skipping is effected upon closure of points 90b which cause completion of a circuit from source S, wire 93, wire 101, points 90b, wire 102, points 92a, wire 103, contacts

35 53 (now closed), magnet 24, wire 86 to source S. Energization of magnet 24 will cause the card to skip to the next column and as explained above the action of the punch mechanism, causes rocking of bail 21 to close contacts 23 and 64 and open

40 contacts 63. Contacts 23 take the punch magnet circuit from the control of the more delicate relay points 90b and 92a.

Contacts 64 energize relay magnet 92 causing points 92a to open and the timing of the various operations is such that contacts 23 open to break the punch magnet circuit while points 92a are open.

Upon reopening of contacts 64 at the end of the escapement action, relay magnet 92 is deenergized and closure of its points 92a will repeat the circuit through the punch magnet which will again close contacts 23 and contacts 64. In this manner the relay points 92a are caused to repeatedly energize the punch magnet 24 and such action will

55 continue until the holding circuit of relay 90 is broken at brushes 77, at which time column 57 which is the first column of field E is at the punching station and operations from this point will continue in the same manner as the operations

60 effected in punching the left hand portion of the card. That is, all or part of the E field may be duplicated, part may be key punched and certain sections may be skipped.

The automatic skipping of the E field is effected in the same manner as described for the G field except that the holding circuit is maintained through strip 81 and an "X" hole 85 in the fifty seventh column effects the initial energization of relays 97 and 90.

70 It will be noted that when either of the fields G or E is being skipped, relay points 90a which

lie in the common return line 89 of the selector magnets 10, are open thus preventing the selection of punch interposers if there should be perforations in the skipped field. It is also apparent that if columns 34 and 57 are both "X" punched, both fields will be automatically skipped.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims:

What is claimed is as follows:

1. In combination, master card reading mechanism effective to read successive data designations of a master card, feeding mechanism controlled by said reading mechanism to advance the card one step as an incident to each data designation reading operation, independent means for controlling the operation of said feeding means, and means controlled by said reading means in response to the reading of a special data designation for causing automatic operation of said independent feed control means.
2. In combination, master card reading mechanism effective to read successive data designations in columns of a master card, punching mechanism controlled by said reading mechanism to duplicate the data designations in a blank card, card advancing means operative as an incident to a punching operation, and means controlled by said reading means in response to the reading of a predetermined data designation for causing the operation of said card advancing means independently of the operation of said punching mechanism.

3. In a duplicating machine, record analyzing means for reading a record card column by column, punching mechanism controlled by said analyzing means for punching duplicate data in columns of a blank card, means controlled by a special data designation for causing a series of successive step by step movements of said record card for a predetermined number of columns and further means controlled by said special data designation for preventing the operation of said punching mechanism whereby duplication of the special perforation in the blank card will be suppressed.

4. In combination, a carriage for a control record and reading means for the control record, means controlled by said reading means for initiating a step-by-step advance of said carriage and means controlled by said carriage and independent of said reading means for terminating said advance.

5. In combination, a carriage for a control record, an escapement mechanism therefor, means for reading a control card, means controlled by said reading means for actuating said escapement mechanism and further means controlled by the position of the carriage for causing repeated operation of said escapement mechanism independently of said reading means.

WM. F. GUTGESELL.
